CLAIM

The ornamental design for the lens and frame for a warning light, as shown and described.

DESCRIPTION

FIG. 1 is a perspective view of an embodiment of a lens for a warning light in combination with an embodiment of a frame for a warning light showing my new design;

FIG. 2 is a top plan view of the lens and frame for a warning light of FIG. 1;

FIG. 3 is a right side view of the lens and frame for a warning light of FIG. 1, the left side view being a mirror image thereof;

FIG. 4 is a bottom plan view of the lens and frame for a warning light of FIG. 1;

FIG. 5 is an end view of the lens and frame for a warning light of FIG. 1, the opposite end view being identical thereto;

FIG. 6 is a perspective view of a second embodiment of a lens for a warning light in combination with a second embodiment of a frame for a warning light showing my new design;

FIG. 7 is a top plan view of the lens and frame for a warning light of FIG. 6;

FIG. 8 is a right side view of the lens and frame for a warning light of FIG. 6, the left side view being a mirror image thereof;

FIG. 9 is a bottom plan view of the lens and frame for a warning light of FIG. 6; and,

FIG. 10 is an end view of the lens and frame for a warning light of FIG. 6, the opposite end view being identical thereto.
